CLAIM

The ornamental design for a patient table, as shown and described.

DESCRIPTION

FIG. 1 is a front elevational view of a patient table showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view taken generally from a direction between the front and right sides thereof;

FIG. 8 is an enlarged view of the patient table as shown in FIG. 1;

FIG. 9 is an enlarged view of the patient table as shown in FIG. 2; and,

FIG. 10 is an enlarged view of the patient table as shown in FIG. 7.

The broken lines shown in the drawings represent portions of the patient table that form no part of the claimed design.
